FIG. 1

FIG. 2

FIG. 3

FLY SWATTER

Lay out all or some of the flash cards on the ground. Give your child a fly swatter or spoonful. Say what's on a card or give a clue to what's on a card that is laid out (e.g. for the letter A card say "I'm looking for the letter that starts the word and"). Your child races to hit the card with the fly swatter. If they are correct they get to keep the card. Each card is worth one point. The more cards they get, the more points they get. Record their points so you can track improvement over time. That way it's not like "winning or losing" it is more like competing against themselves to improve.

GONE FISHING

Attach a paper clip to each flash card. Lay the flash cards on the ground or behind a curtain or chair. Hot glue a magnet to a string, tie it to a wooden dowel or pencil and let your children go "fishing" for flash cards. When they catch a card have them read it, say the sound, say the number, etc. OR call out a specific card by saying what's on it and have your child fish for that specific card.

HIDE AND SEEK

Hide flash cards all around your house (tape one to the fridge, the light switch, etc.) and have your children race around the house to find them. When they find them they must say what is on the card, i.e. the correct sound, number, letter, word, etc.

DRILLS

Have your child sit in front of you and go through the cards one by one. If they say the correct answer praise them generously and place the card in a pile on your right. If they say the incorrect answer explain to them the correct answer and praise their effort. Place the missed card in a pile on your left. Once you have gone through all the cards go through the pile on your left again and repeat until all cards receive the correct answer.
